UNITED STATES PATENT OFFICE.

CHARLES DE LOS RICE, OF WEST HARTFORD, CONNECTICUT.

HYDRAULIC HOIST.

Application filed February 15, 1923. Serial No. 619,245.

To all whom it may concern:

Be it known that I, CHARLES D. RICE, a citizen of the United States, residing at West Hartford, in the county of Hartford 5 and State of Connecticut, have invented a new and useful Improvement in Hydraulic Hoists, of which the following is a specification.

This invention relates to those hydraulic hoists which are more particularly adapted to be placed on ships for transferring freight from ship to dock or lighter or from lighter or dock to ship, and which are so designed that a relatively short movement of the hydraulic plunger gives a long travel to the package carrying hook.

In prior apparatus of this character where the cable passes back and forth around a plurality of pulleys mounted relatively on the lifting plunger and on a fixed part of the apparatus so that the movement of the plunger is multiplied at the hook end of the cable, in order to keep the cable taut on the pulleys and cause the hook to lower properly when idle, it has been necessary to add a very heavy weight to the hook end of the cable and such weight makes it difficult and laborious for the freight handlers to carry the hook around and engage it with and disengage it from the packages of merchandise.

The object of the present invention is to provide an apparatus of this nature with means for feeding the cable outward when the plunger is lowered, and arrange such means so that it is idle and performs no work or offers no resistance when the plunger is raised for lifting the hook, whereby the employment of a heavy weight at the hook end of the cable is obviated and the manipulation of the hook is made easy.

This object is attained in the apparatus illustrated by arranging mechanism which is actuated by the up and down movement of the plunger in such manner that it will be engaged with the cable beyond the operating pulleys and feed the cable outward when the controlling valve is released and the plunger descends, and be disengaged from the cable when the controlling valve admits pressure to the cylinder and the plunger rises.

In the accompanying drawings Figure 1 shows a side elevation of a hoist constructed according to this invention, with the cable omitted. Fig. 2 shows a front elevation of the hoist. Fig. 3 is a top view. Fig. 4 is a transverse section on the plane indicated by

the dotted line 4-4 on Fig. 2. Fig. 5 is a side view of the upper end of the control valve rod, its support and the valve operating lever. Fig. 6 is a section of one of the frame beams, showing the clamp for holding the fixed end of the cable, on plane indicated by the dotted line 6-6 on Fig. 2. Fig. 7 shows, on larger scale, a side elevation of the mechanism that is actuated by the movement of the plunger for feeding the cable outward. Fig. 8 is a section on the plane indicated by the dotted line 8-8 on Fig. 7, looking down. Fig. 9 is a side elevation of the control valve. Fig. 10 is a horizontal section of the valve on the plane indicated by the dotted line 10-10 on Fig. 9, looking up. Fig. 11 is a section of the valve on the plane of the dotted line 11-11 on Fig. 9, looking in the direction indicated by the arrows. Fig. 12 is a section of the valve on the plane indicated by the dotted line 12-12 on Fig. 10. Fig. 13 is a section of the cable pulleys carried on the upper end of the plunger. Fig. 14 is a section of the lower end of the cylinder.

The frame of the apparatus illustrated comprises two T-beams 15 which are arranged vertical and parallel, with their lower ends fastened to a lower deck 16 of the vessel and their upper ends extending up through the upper deck 17 the necessary distance to provide a track of suitable length for guiding the upper end of the hydraulic plunger 18. The plunger is capable of movement up and down in the cylinder 19 that has outwardly extending forked wings 20 which embrace and are fastened to the frame beams so as to support the cylinder vertically between the beams.

Fastened to the lower head of the cylinder is a yoke 21 carrying, in the form shown, four pulleys 22, 23, 24 and 25, and fastened to the upper end of the plunger is a yoke 26 carrying four pulleys 27, 28, 29 and 30, Fig. 102. The number of stationary pulleys attached to the cylinder and the number of travelling pulleys carried by the plunger may of course be varied according to desire. The pulleys may be mounted on anti-friction bearings 300 arranged on a tubular axle 301 suitably packed so they can all be lubricated from a common source. The plunger yoke has outwardly extending forked wings 31 which embrace the webs of the T-beams 110 and guide the upper end of the plunger in its travel up and down. Blocks 32 prefer-

ably of water-proofed wood are desirably inserted in the opening in the wings and fitted to the beam webs so as to provide efficient bearing surfaces between the fixed 5 beams and the movable plunger yoke, Figs. 2, 7.

Mounted on one of the frame beams near the lower end of the cylinder is a drum 33 attached to which is a ratchet wheel 34, 10 Figs. 2, 4. The axle 35 of the drum has a squared end for the application of a crank and a pawl 36 is mounted on the bracket 37 that supports the drum, in position to be engaged with the ratchet wheel and prevent the drum from rotating backward. 15 Attached to the same frame beam near the upper end of the cylinder is a clamp 38, Figs. 2, 6, which comprises two plates that are adapted to be forced together by the screw and nut 39 for gripping the fixed end 20 of the lifting cable. Mounted on a bracket fastened to the frame beam on the other side of the cylinder near the lower end is an idler pulley 40 and above this is an idler pulley 41, Figs. 1, 2.

Connected to the yoke which is mounted on the upper end of the plunger is the upper end of a rack bar 42. This rack bar is movable up and down in a trough-shaped 30 guide 43 that is connected by brackets 44 to the frame beam. Engaging with this rack is a pinion 45 mounted on an arbor 46 that is supported by a bracket 47 attached to the frame beam. A roll 48 mounted on a 35 bracket 49 holds the rack in proper mesh with the pinion, Figs. 7, 8. Fastened to the outer end of the arbor 46 is a wheel 50 the peripheral surface of which is desirably covered with leather. As the plunger 40 travels up and down the rack moves with it, and by engagement with the pinion rotates this wheel in one direction as the plunger 45 goes up and in the opposite direction as the plunger goes down. Pivottally mounted on a bracket 51 fastened to the frame beam near the top of the cylinder is an arm 52 which carries a wheel 53 that also desirably has its peripheral surface covered with leather. This small wheel 53 is located 50 opposite the large wheel 50 and the space between them is in line with the outer periphery of the idler pulley 41, Fig. 8. Fastened to the swinging arm is a spring plate 54 the lower end of which is connected 55 by a link 55 with an angle lever 56 which is mounted on a bracket 57 fastened to the side beam. Hinged to the angle lever is a rod 58, the outer end of which is normally drawn up by a spring 59, Fig. 7. The 60 spring tends to lift the rod and turn the angle lever in such direction that the spring plate swings the arm in and causes the small wheel to press against the large wheel, or the cable which passes between them.

65 The upper end of the valve rod 60 is con-

nected above the upper deck with an angle lever 61 that is pivoted on a bracket 62 fastened to the frame beam, and that has a handle 63 by means of which the lever may be rocked for raising or lowering the 70 valve rod, Figs. 1, 5. Mounted on the valve rod is a roller 640, Figs. 7, 8, which extends over the rod 58 that is drawn up by the spring 59 and that tends to hold the little wheel in contact with the large wheel. 75 When the valve rod is depressed by means of the operating handle this roll engages and pushes down the rod 58 and swings the angle lever 56 in such manner as to carry the little wheel away 80 from the large wheel. Clamped on the valve rod near the upper end of the cylinder is an arbor carrying a roll 64 and clamped on the valve rod below the lower end of the cylinder is an arbor carrying a roll 85 65. Extending from the rack bar near the lower end is a pin 66 which when the rack is near the lower limit of its travel engages the lower roll 65 mounted on the valve rod so as to move the valve rod down, and which 90 when the rack bar is near the upper limit of its travel engages the upper roll 64 in such manner as to lift the valve rod. The clamps are adjustable on the valve rod so that the time of engagement of the pin with 95 these rolls may be varied for altering the time of the shifting of the valve rod. The upper end of the valve rod passes loosely through a housing 67 and a cap 68 which fits on the housing to close the opening 100 therethrough without obstructing the lateral movement of the valve rod, Fig. 5. The lower end of the valve rod is connected with the valve lever 69, Figs. 9, 10, which is fastened to the arbor 70 that has an arm 105 71 within the valve casing 72, which arm carries the valve 73. The valve has a recess 74 in its seating face, and it is adapted to be swung across the ports 75, 76, Fig. 11, 110 as the valve rod is moved up and down. The power supply pipe 77 from the source 115 of power, communicates with the valve chamber 78 back of the valve. A pipe 79 connects the port 75 with the lower end of the cylinder below the plunger, and a discharge pipe 80 leads from the port 76 to any suitable point. When the valve is at 120 one limit the port 75 is open and power is admitted from the pipe 77 to the cylinder through the pipe 79. When the valve is at the other limit the port 75 is cut off from the power but opened to the port 76, and then the power beneath the plunger 125 exhausts through the pipe 79, valve recess and port 76 to the discharge pipe 80. In Fig. 11 the valve is shown in neutral position. Above the upper deck mounted on a pedestal 81 is a pulley 82 with its inner periphery in line with the opening between the large wheel 50 and small wheel 53 on 130

the side of the frame, and depending from this pedestal is a tube 84 in which is fitted a tubular cable guide 85.

The fixed end of the cable to be used with this apparatus is designed to be wound upon the drum 33 until the cable is approximately the maximum length that will be required. The cable is then carried up and passed through the clamp 38 which is tightened so as to firmly grip the cable and relieve the drum from strain. From the clamp the cable passes over the pulley 27 on the plunger, down around the pulley 22 at the lower end of the cylinder, up around the pulley 28 on the plunger, down around the pulley 23 on the cylinder, up and around the pulley 29 on the plunger, down around the pulley 24 on the cylinder, up around the pulley 30 on the plunger, and down around the pulley 25 on the cylinder. It is then carried up on the inside of the lower idler pulley 40 and around the outside of the upper idler pulley 41 and between the large and small wheels and through the guide tube 83 and over the guide pulley 82 above deck. From there it is led by the usual means to the commonly used boom. With the particular design illustrated the travel of the plunger multiplies the travel of the work or hook end of the cable eight times so that if the plunger has a travel of nine feet the hook end of the cable will be carried seventy-two feet.

When the handle is turned by an operator so as to lift the valve rod and open the valve the fluid under pressure, which may be oil, is allowed to enter the cylinder and lift the plunger, the exhaust at this time being closed. The downward movement of the valve rod for this purpose through the mechanism described moves the small wheel away from the large wheel on the side of the frame so that as the large wheel is rotated it performs no work, that is, the cable is not gripped between these wheels when the plunger is raised and the hook end of the cable is being drawn up. When the operator moves the handle in the opposite direction the valve is turned so as to shut off the pressure and open the exhaust, and then the fluid escaping from beneath the plunger allows the plunger to lower and the hook end of the cable to pay out. As the valve rod is moved in this direction for this purpose the roll carried by the valve rod is lifted from the rod which is connected with the swinging arm that carries the small wheel, and allows the spring to draw the rod so that the small wheel will move in and cause the cable to be gripped between the wheels. With the parts in this relation as the large wheel is rotated by the downward movement of the rack, the cable beyond the operating pulleys is fed up just as fast as the descending plunger slacks the cable, so that

the cable is kept tight on the pulleys and the hook end of the cable is free to drop without the addition of a weight. When the valve is turned for again admitting pressure and the plunger is moved upward, the movement of the valve rod causes the little wheel to be carried away from the large wheel and releases the cable. In other words when the plunger descends and the cable is paid out the large and small wheels co-operate to keep the cable taut and feed out the free end, but when the plunger is lifted for raising the free end of the cable this auxiliary feed mechanism is released from the cable. Should the cable take-up mechanism fail to properly function, owing to wear or other cause, the cable is retained on the lower pulleys by bars 200 held by arms 201 fastened to the lower yoke, Figs. 2, 4.

The operator, of course, can shift the valve at any point of the travel of the plunger for stopping or changing its movement. However, should the operator not operate the valve the stop pin on the rack will engage the wheels that are mounted on the valve rod, near the limits of movement of the rack and move the valve rod so as to turn the valve into neutral position and stop the movement of the plunger.

In the preferred construction the cylinder is of cast iron bored from end to end and the plunger is tubular and slightly less in diameter than the bore of the cylinder. A flexible packing 180 held in place by a ring 181 closes the joint between the plunger and the upper end of the cylinder. The upper end of the plunger is closed by a plug 182 to which the upper pulley yoke is fastened, Fig. 2. At the lower end the plunger has a head 183 which is fitted to the cylinder, Fig. 14. The plug at the top and head at the bottom of the plunger are held together by a rod 184. In the periphery of the head are spiral grooves 185 which permit the passage of oil or other pressure lubricant up into the cylinder about the plunger. With this construction the plunger is guided at the lower end by the head and at the upper end by the wings 31 that extend from the upper yoke to the upright T-beams so that the plunger can be readily centralized and guided from its extreme ends at all times.

The invention claimed is:—

1. A hydraulic hoist having co-operating stationary and traveling pulleys for paying out and drawing up cable, a hoisting cable passing around said pulleys, means for causing said pulleys to approach and recede with relation to each other, and auxiliary means adapted to grip the hoisting cable for paying out cable, operated in conjunction with the movements of the means for causing the approach of the traveling pulleys.

2. A hydraulic hoist having sets of co-

- operating pulleys for paying out and drawing up cable, a hoisting cable passing around said pulleys, means for causing the pulleys to approach and recede with relation to each other, and rotatable auxiliary means adapted to grip said hoisting cable between them for paying out cable, operated in conjunction with the relative movements of the pulleys.

10. 3. A hydraulic hoist having co-operating stationary and traveling pulleys for paying out and drawing up a hoisting cable, a movable plunger carrying the traveling pulleys, and auxiliary means actuated by the movements of the plunger adapted to grip and pay out the hoisting cable when the traveling pulleys are moved toward the stationary pulleys.

4. A hydraulic hoist having co-operating stationary and traveling pulleys for paying out and drawing up a hoisting cable, and auxiliary means adapted to engage and grip a hoisting cable between them and keep the cable taut on the pulleys when the traveling pulleys are moved toward the stationary pulleys.

5. A hydraulic hoist having co-operating stationary and traveling pulleys for paying out and drawing up cable, a hoisting cable passing around said pulleys, and auxiliary pulleys on the work side of the operating pulleys adapted to grip the hoisting cable between them and pay out said cable when the traveling pulleys are moved toward the stationary pulleys.

6. A hydraulic hoist having a plurality of stationary pulleys and a plurality of traveling pulleys movable toward and from each other for paying out and drawing up cable, a hoisting cable passing around said pulleys, and auxiliary pulleys on the work side of the sets of co-operating work pulleys adapted to grip between them and pay out said cable when the traveling pulleys move toward the stationary pulleys.

7. A hydraulic hoist having a cylinder, a plunger movable into and out of the cylinder, stationary cable pulleys, cable pulleys movable with the plunger, a hoisting cable passing around said pulleys, and auxiliary means operatively controlled by the movements of the plunger for paying out cable when the movable pulleys approach the stationary pulleys.

8. A hydraulic hoist having a cylinder, a plunger movable into and out of the cylinder, a yoke supporting a plurality of cable pulleys attached to the cylinder, a yoke supporting a plurality of cable pulleys mounted on the plunger, a cable passing around said pulleys and auxiliary means for paying out cable when said plunger pulleys approach said cylinder pulleys.

9. A hydraulic hoist having a cylinder, a plunger movable into and out of the cylinder, stationary cable pulleys, cable pulleys movable with the plunger, auxiliary pulleys and mechanism operably connected with the plunger for rotating the auxiliary pulleys and causing them to pay out cable when the movable pulleys approach the stationary pulleys.

10. A hydraulic hoist having a cylinder, a plunger movable into and out of the cylinder, stationary cable pulleys, cable pulleys movable with the plunger, auxiliary pulleys, and a rack movable with the plunger for rotating the auxiliary pulleys and causing them to pay out cable when the movable pulleys approach the stationary pulleys.

11. A hydraulic hoist having a cylinder, a plunger movable into and out of the cylinder, cable pulleys attached to the cylinder, cable pulleys mounted on the plunger, and auxiliary means operated by the movements of the plunger to pay out cable when the pulleys on the plunger approach the pulleys connected with the cylinder.

12. A hydraulic hoist having a cylinder, a plunger movable into and out of the cylinder, cable pulleys attached to the cylinder, cable pulleys mounted on the plunger, auxiliary pulleys adapted to pay out cable when the pulleys on the plunger approach the pulleys connected with the cylinder, a valve and connections for admitting pressure to and exhausting pressure from the cylinder, means for operating the valve, connections between the plunger and auxiliary pulleys for rotating the auxiliary pulleys, and connections between the valve operating means and the auxiliary pulleys for rendering them operative and inoperative according to the condition of the valve.

13. A hydraulic hoist having a cylinder, a plunger movable into and out of the cylinder, a valve for admitting pressure to and exhausting pressure from the cylinder, means for actuating the valve, stationary and traveling cable pulleys for paying out and drawing up cable, auxiliary pulleys adapted to grip and pay out cable when the main pulleys operate to pay out cable, and means for controlling the operation of the auxiliary pulleys actuated from the plunger and valve actuating means.

14. A hydraulic hoist having a cylinder, a plunger movable into and out of the cylinder, stationary and traveling cable pulleys for paying out and drawing up cable, and auxiliary pulleys operated by the movements of the plunger and adapted to grip and pay out cable when the main pulleys operate to pay out cable.

15. A hydraulic hoist having a cylinder, a plunger movable into and out of the cylinder, a valve and valve actuating means for controlling pressure in the cylinder, stationary cable pulleys, pulleys mounted on

the plunger, and auxiliary pulleys actuated by the movements of the plunger and controlled by the valve operating means for gripping the cable when the plunger carries its pulleys toward the stationary pulleys.

16. A hydraulic hoist having a cylinder, a plunger movable into and out of the cylinder, a valve and valve actuating means for controlling pressure in the cylinder, stationary cable pulleys, pulleys mounted on the plunger, auxiliary pulleys, a rack connected with the plunger for causing the rotation of the auxiliary pulleys, means on said rack adapted to shift the valve actuating means, and means connected with the valve actuating means for causing the auxiliary pulleys to move into and out of operative position.

17. A hydraulic hoist having a cylinder, a plunger movable into and out of the cylinder, a valve for admitting pressure into and exhausting pressure from the cylinder beneath the plunger, stationary cable pulleys, cable pulleys movable with the plunger, auxiliary pulleys, means connected with the valve actuating means for causing the auxiliary pulleys to move toward and from each other, and means connected with the plunger for causing the rotation of one of the auxiliary pulleys.

18. A hydraulic hoist having a cylinder, a plunger movable into and out of the cylinder, a valve and valve actuating means for admitting pressure into and exhausting pressure from the cylinder, stationary cable pulleys, cable pulleys movable with the plunger, auxiliary pulleys, and means operatively connected with the valve actuating means and with the plunger for causing the auxiliary pulleys to move into and out of working relation.

19. A hydraulic hoist having a cylinder, a plunger movable into and out of the cylinder, a valve and valve actuating mechanism for admitting pressure into and exhausting pressure from the cylinder, a plurality of stationary cable pulleys, a plurality of cable pulleys mounted on the plunger, auxiliary pulleys adapted to grip the cable on the work side of the main pulleys, means connected with the valve actuating means for causing the auxiliary pulleys to move into and out of operative relation, means connected with the plunger for causing the rotation of one of the auxiliary pulleys, and a drum for winding the cable and clamp for gripping the cable on the fixed end side of the main pulleys.

CHARLES DE LOS RICE.
